UNITED STATES PATENT OFFICE

PAUL J. McCULLOUGH, OF ST. LOUIS, MISSOURI, ASSIGNOR TO SCULLIN STEEL COMPANY, OF ST. LOUIS, MISSOURI, A CORPORATION OF MISSOURI

CAR TRUCK

Application filed November 5, 1928. Serial No. 317,264.

This invention relates to car trucks of the type that are equipped with lateral motion devices for the bolster, consisting of horizontally-disposed rollers arranged transversely of the bolster between roller seats formed on the underside of the end portions of the bolster, and roller seats formed in the spring caps that rest upon the bolster supporting springs.

10 The main object of my invention is to provide a car truck of the general type mentioned, in which the spring caps that serve as seats for the rollers on which the bolster rests, are provided at their ends with extensions 15 that project laterally beyond the side edges of the bolster and bear upon bolster supporting springs whose major portions are located beyond or outside of the spring plank, thereby producing a car truck that has sufficient bolster supporting spring capacity to 20 take care of exceptionally heavy loads or abnormal loads and whose spring caps serve as load carrying members that effectively equalize the bolster load on the bolster supporting springs.

Another object is to provide a car truck that is equipped with a spring plank of novel form.

Figure 1 of the drawings is a fragmentary 30 top plan view, illustrating my invention and showing a portion of one side frame, a portion of the bolster, and one group of bolster supporting springs.

Figure 2 is a fragmentary side elevational view of the structure shown in Figure 1.

Figure 3 is a horizontal sectional view, taken on the line 3-3 of Figure 2, looking in the direction indicated by the arrows; and

Figure 4 is a vertical sectional view, taken 40 on the line 4-4 of Figure 2.

My improved car truck comprises two side frames A, a transversely-disposed bolster B whose end portions are positioned in openings in the side frames, a transversely-disposed spring plank C arranged under the bolster and interlocked or connected in any preferred manner with the side frames, two groups of bolster supporting springs, herein-after more fully described, a spring cap D 45 associated with each of said groups of springs

and arranged at the upper end of the springs, and a set of rollers E interposed between each of said spring caps and the opposed end portion of the bolster. The rollers E extend transversely of the bolster and are arranged 55 in seats formed in the top faces of the spring caps D and in the underside of the end portions of the bolster and operate in the same way as conventional lateral motion devices of the roller type.

60 The bolster supporting springs, instead of being arranged entirely within the zones in which the end portions of the bolster lie, are arranged so that the major portions of some of the springs in each group of springs 65 will be located at points outside of or beyond the side edges of the bolster and in the vertical planes of the columns F of the side frames that guide the bolster and which form the sides of the bolster-receiving openings 70 in the side frames. In the form of my invention herein illustrated each group of bolster supporting springs comprises a set of center springs G that lie directly underneath the end portion of the bolster and two end 75 springs G' whose major portions are located at points beyond or outside of the bolster, the set of center springs G being made up of four, five or any preferred number of 80 springs.

In order that the load on the bolster will be effectively equalized by the bolster supporting springs and distributed substantially uniformly or evenly to all of the springs of each group, each of the spring caps D is provided at its ends with extensions D' that lap over and bear upon the end springs G' of the group of springs with which said cap cooperates. The center set of springs of each group are carried or supported by the spring 85 plank C, and preferably rest upon a removable spring seat member C' positioned on the spring plank, but the end springs G' of each group are carried or supported by horizontally-disposed spring seats H, shown in 90 broken lines in Figure 2, that are formed by horizontally-disposed integral portions of the side frames that are located at the lower 95 ends of the columns F. The top faces of said spring seats H preferably extend flush with 100

the top face of the spring plank, but if desired, the spring seats H can be arranged in a slightly lower horizontal plane and shims can be interposed between the same and the end springs G'. The columns F are constructed in such a manner that they will serve as partial housings for the end springs G' and also as guides for the end extensions D' of the spring caps. In the truck herein shown each of the columns F comprises two vertically-disposed side pieces that are spaced apart a distance equal to the width of the end extensions G' of the spring caps, as shown in Figure 3. By constructing the truck in this manner I am able to use a relatively narrow bolster and side frames whose tension members have relatively short beams A' arranged at the lower side of the bolster-receiving opening, and at the same time have sufficient bolster supporting spring capacity to take care of exceptionally heavy loads or abnormal loads, this, of course, being due to the fact that the spring caps D which form seats for the lateral motion devices of the truck are so constructed and arranged that they will serve as load carrying members which transmit the load on the bolster to springs that are arranged in the zone of the bolster and in zones that are located outside of or beyond the side edges of the bolster.

The spring plank C of my improved truck, instead of being formed channel-shaped throughout its entire length, as is the usual practice, is provided adjacent its ends with recesses or inwardly-projecting pockets C², shown in Figure 1, so as to permit the end springs G' to be arranged nearer to the springs G that lie in the zone of the bolster, this form of spring plank being highly advantageous, in that it permits the bolster supporting springs to be very compactly arranged and also permits the center beams A' of the tension members of the side frame to be made of minimum length. Still another advantage of such a spring plank is that the inwardly-projecting portions of the side flanges of the spring plank that form the recesses C² for the end springs serve as spacing devices for the center springs G that tend to insure said center springs remaining in properly spaced relation. The spring plank C may be connected to the side frames A in any preferred manner, but I prefer to equip the beams A' of the side frames with upwardly-projecting lugs A², as shown in Figure 2, that project into holes formed in the web of the spring plank.

Having thus described my invention, what I claim as new and desire to secure by Letters Patent is:

1. In a car truck, the combination of a side frame provided with a bolster opening, a bolster having an end portion that projects into said opening, a group of supporting springs for the bolster comprising end

springs whose major portions are located outside of or beyond the side edges of the bolster, a cap at the upper end of the springs provided with extensions that bear upon said end springs, and rollers arranged so as to bear directly on said cap and on the underside of the bolster.

2. In a car truck of the kind described in claim 1, columns on the side frame that partially house said end springs and serve as guides for the extensions on said spring cap.

3. In a car truck of the kind described in claim 1, integral portions on the side frame that serve as seats for said end springs, and columns on said side frame that partially house said end springs and serve as guides for the extension on said spring cap.

4. In a car truck, the combination of a side frame provided with a bolster opening, a bolster whose end portion projects into said opening, columns at the sides of said opening that guide the bolster, supporting springs for said bolster arranged in the plane of said side frame and comprising end springs whose major portions are located outside of or beyond the side edges of the bolster, and a lateral motion device for equalizing the bolster load on said springs, provided with portions that move vertically within said columns.

5. In a car truck, the combination of a side frame provided with a bolster opening, a bolster whose end portion is positioned in said opening, supporting springs for the bolster comprising center springs that are arranged underneath the bolster and end springs whose major portions are located at points beyond the side edges of the bolster, and a spring plan combined with the side frame and provided adjacent its ends with recesses for receiving said end springs.

6. In a car truck, the combination of a side frame provided with columns that form the sides of a bolster opening, a bolster having its end portion positioned between said columns, a spring plank arranged under the bolster and connected to the side frame, a center set of supporting springs for the bolster carried by the spring plank, additional supporting springs for the bolster whose major portions are arranged within the columns, supporting members for said additional spring carried by the side frame, a spring cap that bears upon all of said springs, and rollers interposed between said spring cap and the bolster.

7. In a car truck of the kind described in claim 6, side flanges on the spring plank shaped so as to form inwardly-projecting pockets at the side edges of the spring plank in which said end springs are positioned.

PAUL J. McCULLOUGH.
